UNITED STATES PATENT OFFICE.

ROBERT S. CADE, OF CANTON, OHIO.

MOLD FOR CONCRETE WINDOW OR DOOR FRAMES AND TRIMS.

1,326,251.

Specification of Letters Patent. Patented Dec. 30, 1919.

Application filed January 13, 1919. Serial No. 270,844.

To all whom it may concern:

Be it known that I, ROBERT S. CADE, a citizen of the United States, residing at Canton, in the county of Stark and State of Ohio, have invented new and useful Improvements in Molds for Concrete Window or Door Frames and Trims, of which the following is a specification.

This invention relates to a mold for making concrete window or door frames and trims.

One object of the invention is to provide a mold embodying interchangeable parts capable of being readily and conveniently assembled to produce any desired style of door or window frame with conventional or special inside and outside trims and having any desired surface finish.

A further object of the invention is to provide a mold which is capable of being readily set up and taken down when required, which has its various parts so constructed as to be easily removed from the form after the latter has set, and which is constructed in such manner as to be capable of being set up and used upon a building in the course of construction without interfering with the door-ways or windows of the building.

30 A further object of the invention is to provide a form for door-ways or windows which is capable of carrying with it special trims to be applied to the facings of such doors or windows, and by the use of which these trims are precluded from becoming broken or injured.

With these objects in view, together with others which will appear as the description proceeds, the invention resides in the novel 40 construction, combination and arrangement of parts, all as will be described more fully hereinafter, illustrated in the drawings, and particularly pointed out in the claims.

In the drawings:—

45 Figure 1 is a horizontal sectional view taken through one of the upright portions of a mold for forming a window frame.

Fig. 2 is a side elevation of a part of the window frame mold.

50 Figs. 3 and 4 are horizontal sectional views taken through the uprights at each side of the door frame and illustrating the molds employed for making such forms, and

55 Fig. 5 is a detail view illustrating one of the improved clamping devices.

An important feature of the invention is

that the molds are capable of being expanded or contracted to constitute the forms for window or door frames of various sizes, and therefore the molds are made up of interchangeable parts or sections, and are equipped with improved fastening devices for easily and quickly securing the parts firmly together or to permit of dismembering the same. Furthermore, the molds are formed of sections of light weight and capable of being easily handled, and the molds may be assembled in upright position or may be laid flat and left to so remain after the plastic has been poured into the same. In instances where special facings or trims are to be applied to the plastic form, these facings are inserted in the molds before the coarse plastic is applied thereto, and retaining rods of approved construction and assemblage are placed within the molds to hold these facings or trims in proper position during the molding operation.

In Figs. 1 and 2 of the drawings there is illustrated a mold or form for constructing a window frame, and the mold in this instance comprises side plates 6 formed of thin sheet metal and bent so as to provide a frame of the desired shape or configuration. The sections 6 extend inwardly near one end as at 7, and are provided with forwardly projecting flanges 8 to retain between them the jamb 9 formed preferably of wood. This jamb is to be securely anchored in the plastic constituting the frame, and may be provided upon its outer face with suitable grooves or channels as shown to accommodate the projections upon the slidable sashes for the window. The jamb 9 is detachably secured to the mold flanges by the screws 10, and this jamb constitutes an end for the mold. The inner face of the jamb may be channeled as at 11 to enable the plastic material to enter and form a retaining rib, thus enabling the jamb to be securely held to the plastic frame. The jamb is also provided with inwardly extending anchoring bolts 12, having the nuts 13 spaced thereon, and it will be understood that the plastic after having become set around the anchoring bolts will firmly hold the jamb to the frame.

The mold may be provided with a suitable core to provide a pocket or channel indicated at 14 for the accommodation of the sash weights to be used in connection with the sliding sashes. This core may be formed of any suitable material and may be applied

to or removed from the mold in any desired manner.

As shown in the drawing, the sides, lintel and sill of the window frame constructed in accordance with the invention are of greater thickness than the walls of the building, and therefore the inner ends of the mold plates 6 are turned or bent inwardly as at 16; the edges of such portions terminating in the plane of the wall surfaces. Each of these inwardly turned or bent flanges is engaged by a plate 17, the latter projecting at one longitudinal edge beyond the plane of the mold side, and these projecting portions are provided at spaced intervals with openings of a size suitable to snugly receive the larger ends of the wedge keys 19. The mold sides are each equipped with an angle member 18 so arranged as to lie against the faces of the plates 17, and these angle members have openings registering with the openings in the said plates 17 whereby the keys 19 may project therethrough. The keys 19 are provided at a point substantially midway their ends with openings to receive the locking wedges 19'. It will be observed that the key at one end is headed as at 20 and this head engages with one face of plate 16, so that the application of the wedge to the key 19 will cause the said head to firmly bind against the said flange. The sides 6 of the mold are connected by the bars or rods 21, and these rods extend through suitable openings in the sides of the walls 6, and the protruding ends of these rods are operated upon by the wedges and firmly bound in the brackets. After the mold sides have been placed properly and the rods 21 applied, the wedges 19' are forced into the openings in the keys 19, and the rods are held against movement and are bound firmly against the bracket portions 17.

The wall mold sections are in a similar manner connected to the plates 23 of the wall molds, the sections having angle brackets 24 thereon to coöperate with each other in forming a rigid structure. These brackets abut when the wall mold plates are properly assembled, and the application of a key 19 and wedge 19' in the manner above described will cause the brackets 24 to be firmly held together. A tie or binding rod 26 may also be used in connection with the last named angle brackets.

In Figs. 3 and 4 I have illustrated the same principle carried out in forming the side members of a concrete door frame. In this form of the invention, the said plate 27 connects the inner ends of the mold sections, and is to be removed with the form after the plastic has become set. This plate is attached to the forwardly projecting flanges of the mold sides by the bolt 28, and is recessed on its inner surface in such man-

ner that a stop 29 of plastic will be formed after the plastic hardens. The lock catch 30 is formed of metal and is assembled with the mold sections when the form is set up, and this catch is provided with an anchoring bolt 31 to be embedded in the plastic when the latter is applied to the mold. The plate 30 may be backed with a friable core 32, which may be removed after the plastic sets. After the concrete or other substance hardens, the mold sections will be removed, and the plate 30 will be anchored firmly in the door frame in proper position to receive the lock bolt latch of the door to be used in the frame. The core 32 may be picked out after the concrete has set.

In Fig. 4 there is illustrated a cross sectional view of the door jamb, and the mold sides and end are identical with those described in connection with the frame mold for the opposite side of the door frame. In this instance, however, the hinge plate 33 is secured in the plastic mass, and is anchored therein by the bolt 34. The plate 33 carries a barrel or knuckle 35 at its outer end, upon which will be pivoted the door. The bolts 31 and 34 may each be provided with a number of nuts as shown to enable the same to be securely embedded in the hardened plastic.

In instances where the door or window frame is to be provided with a special inside or outside trim, the trim 39 is molded, formed or built and is applied to the interior of the mold prior to the pouring operation. The trims may be held in proper position by the tying or retaining rods 40, and these rods also assist in holding the mold sections properly centered prior to and during the molding process. After the mass has become set, the pins or rods may be easily removed, as will be understood.

From the foregoing it is obvious that I have provided a mold of extremely simple and improved construction for forming window and door frames, and which can be readily set up and taken down when required. Various changes in the details of construction and arrangement of parts may be resorted to without departing from the spirit of the invention as defined by the claims.

I claim:

1. In a mold of the class described, plates constituting the sides of the mold, brackets upon each plate, rods extending from one plate to the other and into said brackets, and fastening members coöperating with said brackets and rods for holding the latter in position.

2. In a mold of the class described, plates constituting the sides of the mold, brackets for each plate, rods extending through the mold and connecting the said sides, a key for uniting coöperating brackets, and means

coöperating with each key to force the rod ends into frictional engagement with the said brackets.

3. In a mold of the class described, plates 5 constituting the sides of the mold, brackets upon each plate, rods extending from one plate to the other and into said brackets, fastening elements coöperating with said brackets and rods for holding the latter in 10 position, and means coöperating with said fastening elements for forcing the rod ends into frictional engagement with the said brackets.

4. In a mold of the class described, plates 15 constituting the sides of the mold, brackets upon each plate, rods extending from one plate to the other and into said brackets, and wedges coöperating with said brackets and rods for holding the latter in position.

20 5. In a mold of the class described, plates constituting the sides of the mold, brackets for each plate, rods extending through the mold and connecting the said sides, a key for each bracket, and a wedge extending through each key to force the rod ends into frictional engagement with the said brackets.

6. In a mold of the class described, plates 25 constituting the sides of the mold, tying and alining rods carried by each plate, spacing rods connecting said plates, and a wedge member on each plate to engage the said spacing rod ends to hold the same in assembled position.

30 7. In a mold of the class described, plates constituting the sides of the mold, brackets for the said plates having openings therein, connecting rods extending from one plate to

the other and protruding at their ends into 40 said brackets, a key for each bracket to project through the opening therein and each key having a wedged aperture, and a wedge for each of said apertures to bind the said rod ends into engagement with said brackets.

8. In a mold of the class described, 45 sectional side plates, angle members carried by certain of said plates and lying flush upon portions of the adjacent sections, the said portions and angle members having registering openings therein, a headed key extending through said openings, said key having an aperture therein, rods connecting the sides of the mold, and wedges extending through said apertures to bind said rod ends to the angle members and to clamp the said 50 angle members and plate portions together.

9. In a mold of the class described, plates 55 constituting the sides of the mold, an end plate detachably connecting said side plates, and anchoring means carried by said end plate and extending into the interior of said mold.

10. In a mold of the class described, sides 60 for the mold, an end plate having channels on its interior surface, and anchoring bolts extending through said end plate near said channels and into the interior of said mold.

11. In a mold of the class described, sides 65 for the mold, an end member detachably connected to the mold sides, an element detachably carried by said end member and one of the sides, and an anchoring device on said element extending to the interior of said mold.

In testimony whereof I affix my signature. 70
ROBERT S. CADE.
